RELAY

Maynard A. Babb, North Bergen, N. J., and Samuel J. A. M. Bagno, New York, N. Y., assignors to Duro Test Corporation, North Bergen, N. J., a corporation of New York

Application December 23, 1938, Serial No. 247,404

16 Claims. (Cl. 200—87)

The present invention relates primarily to electro-magnetic control units useful for starting and operating devices having thermionic electrodes, including among others neon and mercury vapor lamps.

As conducive to a clear understanding of the invention it is noted that where part of the line voltage is consumed in special mechanisms required to heat the electrodes, with their associated controls such as time delay relays or bimetallic thermal strips or other devices operated by separate heating elements, resort to transformers or complicated resonant circuits would be required to step up the line voltage sufficiently for enabling the arc to strike in a gas or vapor lamp.

Among the objects of the invention are to provide a unit of rugged and inexpensive construction, effective to assure the expeditious starting and maintenance without sputter of the operation of thermionic electrode devices of the above type, and dispensing with the need for time delay relays, thermal strips or other devices operated by separate heating elements or the need for a transformer, or for a complicated resonant circuit.

Another object is to provide a unit of the above type which automatically opens the thermionic or electrode filament circuit after the arc strikes and affords ballast mechanism for limiting the current to the lamp during operation and is operative and remains operative for its purpose even though the line voltage varies several volts one way or the other as may occur in practice, especially with small power plants.

Another object is to provide a device of the above type which is so compact that it may readily be incorporated as a unit with the lamp or disposed at will in coves or other convenient places in a room to be illuminated.

The invention briefly stated, involves a unit including a low reluctance closed yoke, an associated high reluctance yoke and an electro-magnetic coil common to both of said yokes, a minute air gap being provided in the low reluctance yoke which affords sufficient leakage to attract an armature on the high reluctance yoke, which in turn effects opening of a circuit maker.

In the accompanying drawing in which is shown one of various possible embodiments of the several features of the invention:

Fig. 1 illustrates diagrammatically a preferred form of circuit in which the unit of the present invention is an element, the unit itself being shown in plan view.

Fig. 2 is a front elevation of the unit,
Fig. 3 is a longitudinal sectional view taken on line 3—3 of Fig. 2,

Fig. 4 is a transverse sectional view taken on the line 4—4 of Fig. 3,

Fig. 5 is a perspective view of the elements making up the armature and its yoke, and

Fig. 6 is a perspective view with parts broken away showing the main or low reluctance yoke element.

For a clearer understanding of the setting in which the unit is preferably to be used, reference may be had to Fig. 1 showing such unit as part of the starting and operating circuit for gaseous electric discharge devices, which circuit by itself and apart from the structure of the control unit, is the sole invention of Maynard A. Babb and the subject of his copending application Serial No. 234,710, filed October 12, 1938 and issued April 25, 1939, as Patent No. 2,155,816.

The gaseous electric discharge device comprises a gas or vapor lamp 10 having a gaseous filling such as neon, mercury vapor or the like, and provided with thermionic electrodes 12 and 13 which may each be formed of a roll of electron emissive material such as barium oxide, surrounding a heater filament. One terminal of electrode 12 is connected by a lead 14 to one terminal 15 of a commercial source of alternating current, which may have the usual line voltage of 110 to 120 volts. The other terminal of electrode 12 is connected by lead 18 to contact plate 17 of a circuit maker, coacting with contact arm 16 thereof, which in turn is connected by lead 18 to one terminal of electrode 13. The other terminal of electrode 13 is connected by lead 19 to one terminal 20 of electro-magnetic coil 21, the other terminal 22 of which is connected to the other terminal 23 of the power source. A hand controlled switch 24 may be disposed in either lead 14 or 19.

The control unit in a desirable construction comprises an electro-magnetic coil 21, carried on a spool 26 and in turn mounted upon a closed magnetic yoke or frame, a leg of which preferably extends through the coil. Desirably, said yoke is made up of a stack of E-shaped laminations 27 of iron, held together by varnish or other suitable resin. Over the median leg or bar 28 of the yoke extends the coil 21 and the lateral legs or bars 29 and 30 flank the coil. The ends of the central and lateral legs preferably extend substantially flush with the top of the coil and are connected by a bridging bar 31 of iron also made up of laminations bonded together by varnish or

the like. Thus, the closed magnetic circuit extends through the coil and closely about the sides and ends thereof. The two sets of laminations are secured together in a unitary structure with an intervening air gap, determined preferably by an interposed layer 32 of non-magnetic insulating material, such as paper or the like. For enhancing the security of assembly of the two sets of laminations with respect to each other, the extreme E-shaped laminations are preferably reversed so that the three arms 33 thereof extend downward from the cross bar or beam 34 thereof which extends along the length of the bridging bar 31.

15 The closed magnetic yoke of given dimensions is calibrated to a selectively determined low reluctance, the value of which depends on the characteristics of the lamp or other device to which it is to be applied. This calibration is determined by the length of the air gap or thickness of the paper layer. In practice, that thickness would be generally between .005 inch and .030 inch, the thicker the paper the greater the reluctance. Inasmuch as each line of flux passes through two of the air gaps in series, in the particular embodiment disclosed, the effective length of the air gap traversed would accordingly be between .010 inch and .060 inch. Preferably paper stock of .002 inch or less would be used, and the reluctance determined by the number of sheets of paper used.

In addition to the low reluctance magnetic circuit set forth, the device presents a high reluctance circuit made up of a yoke 35 which extends through the spool 26 of the coil, preferably against the median bar 23 and has two outstanding ends or arms 36 and 37 extending generally at right angles to the laminations, outward beyond the periphery of the spool. Yoke 35 is bridged by an armature 38 provided with a heel piece 39 normally depressed by leaf spring arm 16 to maintain the end of the armature spaced from the lower end 37 of said yoke.

Preferably the leaf spring 16 which is riveted at one end 40 to a stiff insulating carrier strip 41 carries at its free end a contact 42 in normal engagement with a fixed contact 43 mounted on a metal carrier 44 also riveted to said insulating strip 41. Strip 41 is preferably affixed upon the leg 36 of the yoke. For hingedly mounting the armature 38 on leg 36 the latter is preferably bent downward at 45 and affords an outward ledge cut away at its middle to provide a pair of lateral ears 46 notched at their inner or facing edges as at 47 to accommodate the armature at corresponding lateral notches 48 which straddle the thickness of the respective ears 46, with sufficient clearance to permit ready assembly. To lock the armature against lateral shifting between the notches a non-magnetic centering plate 49 is then superposed over the armature, with its reduced end 50 snugly accommodated in the notches 47, rivets 51 forced through said positioning plate 49 and armature 38 maintaining the latter elements in assembled relation.

Preferably the other arm 37 of the yoke piece 38 mounts a shading coil in the form of one or more copper rings 52 snugly engaged about the lug 53 formed by notching said arm as at 54. Desirably the free end of the armature 38 has a pair of non-magnetic rivets 55 therein to prevent freezing of the armature to the yoke 35 in attracted position. The armature 38 and if desired also the yoke 35 is of extremely high permeability, being preferably made of an alloy of

nickel and iron, such as for instance the material sold under the trade-mark "Permalloy".

It will of course be understood that for assembly the yoke 35 is first inserted through spool 26, insulating carrier strip 41 with its contact maker 16, 17 is mounted upon the yoke, as is also armature 38. Thereupon the E-shaped laminations 27 are inserted through the yoke, and the bridging piece is applied and the whole subjected to a varnish bath and compressed.

The yoke 27 of the unit being made up of a multiplicity of iron laminations and having but a small fixed air gap, presents high reactance and low reluctance. The magnetic leakage due to the air gap is however sufficient when the current through the coil 21 exceeds a given minimum to magnetize the yoke 35 sufficiently for attraction of the high permeability armature 38 and thereby to cause its heel 39 to raise the spring arm 16 of the contact maker and interrupt the circuit controlled thereby. The shading coil 52 causes a splitting of phase to enhance the attractive force and inhibit chatter of the armature.

Thus, the low reluctance yoke comprises a frame, the magnetic structure of which is interrupted by minute fixed air gaps but is otherwise continuous. The auxiliary or high reluctance open yoke with the armature carried thereby is arranged in parallel with the low reluctance circuit, and due to the leakage resulting from the presence of the air gaps in the latter, will intercept enough magnetic flux to effect attraction of the armature, when the current through the electro-magnetic coil exceeds a given minimum.

In use of the unit as part of the circuit shown in Fig. 1, the line current upon closing the switch 24 passes through thermionic electrode 12, circuit maker 16-17, thermionic electrode 13 and coil 21, which elements are at that time connected in series across the line terminals 15 and 23. The leakage of magnetic flux at the air gaps 32 of the magnetic yoke, under the current through coil 21 causes attraction of armature 38 and thereby opening of the contact maker 16-17. This results in interruption of the circuit through coil 21 and breakdown of the magnetic field in the magnetic yoke 27 so that the resilient leaf spring 16 recloses. This process is repeated rapidly until electrodes 12 and 13 are sufficiently hot so that successive reactance surges from coil 21 due to the successive opening of contact 16 superadded upon the voltage across the electrodes 12 and 13 while contact 16 is open, causes an arc to be struck between the electrodes. In normal practice it takes as little as one second for such arc to strike.

As long as the arc exists, the current thereof passes to the terminal 23 through coil 21 and is of magnitude such that the magnetic leakage is sufficient to maintain the armature 38 closed and the contact maker 16 open. As long as the arc is maintained, the unit 21 acts as a choke, ballast, or current limiting device for the arc during continuous operation of the lamp. Preferably the unit is so designed that during normal operation the reactance thereof is approximately equal to the resistance of the lamp.

The air gap in the yoke has a two-fold function. It affords enough leakage for operation of the armature and it prevents magnetic saturation of the yoke, should the line voltage be increased by 5 to 10% above that for which the device is primarily designed. For, under those conditions the corresponding increase of voltage

across the unit effects a correspondingly great increase in reactance flux and so does not permit the lamp to take an excessive increase in current.

While, as previously noted the combined choke and contact device has its primary application for starting and operating gaseous electric discharge devices with thermionic electrodes, such as for instance neon and mercury vapor lamps, it is understood that the device is not necessarily limited to such application and it is herein claimed not only for use in such relation but as a piece of electro-magnetic equipment regardless of its particular application or use.

As many changes could be made in the above construction and many apparently widely different embodiments of this invention could be made without departing from the scope of the claims, it is intended that all matter contained in the above description or shown in the accompanying drawing shall be interpreted as illustrative and not in a limiting sense.

Having thus described our invention, what we claim as new and desire to secure by Letters Patent is:

1. A unit of the character described, comprising an electro-magnetic coil, a stationary magnetic yoke member including a frame having a leg extending through said coil, the magnetic structure of said member being interrupted by a minute fixed air gap and being otherwise continuous, a pair of spaced magnetic arms protruding from said member and adapted to intercept magnetic flux due to the leakage resulting from said air gap, and an armature extending between said arms and adapted to be attracted to bridge across the same when the current through said coil exceeds a given minimum.

2. The combination recited in claim 1 in which the effective length of said air gap is selected between .010 and .060 inch for predetermined low reluctance of the magnetic yoke.

3. A unit of the character described, comprising a stationary magnetic yoke member including a frame, the magnetic structure of which is interrupted by one or more minute fixed air gaps and is otherwise continuous, an auxiliary open magnetic yoke extending lengthwise of a portion of said frame and having arms protruding outward from said frame, an armature extending across the extremities of said yoke arms, an electro-magnetic coil encircling said auxiliary magnetic yoke and the corresponding portion of the frame and an armature extending across the extremities of said yoke arms and adapted to be attracted and to close the magnetic circuit thereacross when the current through said coil exceeds a given minimum.

4. A unit of the character described comprising a pair of magnetic circuits, one of said circuits comprising a magnetic frame, all parts of which are relatively immovable and interrupted by one or more minute fixed air gaps and otherwise continuous, the other of said circuits including an open yoke of high reluctance, an armature of high permeability extending across the open ends of said yoke, and an electro-magnetic coil common to said magnetic circuits and adapted to cause attraction of said armature when the current through said coil exceeds a given minimum.

5. A unit of the character described comprising an electro-magnetic coil, a stationary magnetic yoke structure extending through and laterally framing the ends of said coil and having paper laminations thereacross determining a mi-

nute air gap therein, a smaller yoke extending lengthwise through said coil and having arms extending outward from the general plane of said main yoke, and an armature pivotally mounted on one of said arms and adapted to be attracted by leakage flux of sufficient magnitude.

6. A unit of the character described, comprising an iron yoke having a leg and an electro-magnetic coil encircling the latter, said yoke including a rectangular body unitary with said leg and framing said coil, said yoke having a minute air gap affording leakage flux, an armature of high permeability and a yoke carrying the latter and arranged in close contiguity to said air gap to intercept sufficient leakage from said air gap for attraction of said armature when the current through the coil exceeds a predetermined value.

7. A unit of the character described comprising an electro-magnetic coil, a closed low reluctance stationary magnetic circuit structure having a leg extending through said coil and a frame unitary therewith and closely embracing said coil, a high reluctance magnetic circuit including a yoke through said coil and an armature carried thereby exteriorly of said coil, said low reluctance circuit having a minute air gap, which provides sufficient leakage flux for actuating said armature when the current through said coil exceeds a definite minimum.

8. A unit of the character described including an electro-magnetic coil, a laminated yoke of low reluctance having an intermediate leg extending through said coil, a base unitary therewith under said coil, side pieces unitary with said base laterally of said coil and a top bar bridging said side pieces and said leg, said bridging pieces and said leg and side pieces being rigidly connected together with a minute air gap therebetween, spaced magnetic elements protruding outward from the intermediate leg of said yoke from near opposite ends of the coil, and an armature across the outer ends of said magnetic elements and adapted to close magnetic circuit therebetween when the current through said coil exceeds a given minimum.

9. A unit of the character described including an electro-magnetic coil, a laminated yoke of low reluctance having an intermediate leg extending through said coil, a base unitary therewith under said coil, side pieces unitary with said base laterally of said coil and a laminated top bar bridging said side pieces and said leg, said bridging piece and said leg and side pieces being rigidly connected together with a minute air gap therebetween, a high reluctance circuit comprising a yoke of a single stamping extending through said coil to one side of said low reluctance yoke and having out-turned ends protruding beyond said coil and an armature of high permeability pivoted to one of said ends and operated by leakage flux from said low reluctance yoke.

10. A unit of the character described comprising a low reluctance magnetic yoke including a stack of E-shaped laminations an electro-magnetic coil mounted upon the intermediate leg of said yoke, the outer legs thereof flanking said coil, a stack of straight laminations bridging the ends of said three legs, paper lamination between said two sets of laminations and determining a minute air gap for leakage, and a magnetic circuit in parallel with that of said yoke and including two arms and an armature of high permeability bridging therebetween and at the exterior of said coil.

11. The combination recited in claim 10 in

which the outermost of the E-shaped laminations are in reverse positions for super-position of the beam thereof over the bridging piece.

12. A combined choke and circuit maker comprising a stationary magnetic yoke frame of low reluctance, the magnetic structure of which is interrupted by one or more minute fixed air gaps and is otherwise continuous, an electro-magnetic coil encircling a portion of said frame, a second yoke through said coil extending outward at its ends substantially at right angles to said low reluctance yoke, an armature hinged upon one of said ends, a resilient circuit maker arm at right angles to the length of said armature, and across the hinged end thereof, said armature having a heel piece for directly engaging and opening said circuit maker upon the attraction of said armature.

13. The combination recited in claim 12 in which the part of said armature beyond the heel piece is flat and has lateral notches into which extend fingers on the high reluctance yoke to form the hinge mount of the armature.

14. The combination recited in claim 12 in which the hinge of said armature is formed by a pair of fingers on the high reluctance yoke ex-

tending transversely into lateral notches in the armature and in which the armature has a non-magnetic centering piece correspondingly notched.

15. The combination recited in claim 12 in which a non-magnetic stiff insulating strip is mounted upon that end of the high reluctance yoke which carries the armature, which strip in turn carries the circuit maker, the latter comprising a fixed contact and a resilient movable contact arm.

16. A unit of the character described, comprising a stationary, generally rectangular magnetic yoke interrupted by one or more minute fixed air gaps and otherwise continuous, an auxiliary generally U-shaped magnetic yoke lying against a side of said yoke, an electro-magnetic coil closely encircling said leg and said yoke, and closely framed by said yoke, the ends of said U-shaped yoke protruding outward beyond said coil, an armature pivoted to one of said ends and adapted to engage the other of said ends, and a shading coil encircling said other end.

MAYNARD A. BABB.
